[57] CLAIM

The ornamental design for a plant pot, as shown and described.

DESCRIPTION

FIG. 1 is a perspective view of the plant pot;

FIG. 2 is a top view thereof;

FIG. 3 is a side view thereof, the opposite side being identical;

FIG. 4 is a bottom view thereof; and,

FIG. 5 is an enlarged cross section taken along line 5—5 in FIG. 2.

The design is characterized by the overall shape and ornament of the plant pot as shown in the drawings.
